UNITED STATES PATENT OFFICE.

GEORGE H. NOBBS, OF QUINCY, MASSACHUSETTS, ASSIGNOR TO THE PHONOHARP COMPANY, OF EAST BOSTON, MASSACHUSETTS, A CORPORATION OF MAINE.

PLAYING ATTACHMENT FOR ZITHERS.

Application filed November 24, 1917. Serial No. 203,675.

To all whom it may concern:

Be it known that I, GEORGE H. NOBBS, a citizen of the United States, residing at Quincy, in the county of Norfolk and State 5 of Massachusetts, have invented new and useful Improvements in Playing Attachments for Zithers, of which the following is a specification.

This invention has relation to playing attachments for zithers of the type in which 10 spring hammers are employed for impingement upon the strings to produce a single note or a tremolo as desired.

One of the objects of the invention is to 15 provide a construction in which the same member that is actuated to cause the hammer to strike its associated string also serves to damp the vibration of the hammer upon its release and return to normal inactive 20 position.

Another object of the invention is to provide certain other improvements by which 25 the inertia of the hammer head is overcome by the initial movement of the hammer- actuating member and by which certain other desirable results are secured.

According to the present invention, each 30 hammer-actuating member is so constructed and located in reference to the associated spring hammer that, when the latter is at rest, its free end is engaged and held under tension thereby, and, when said member is 35 actuated, it impels the head of the hammer towards the string. This member may be directly engaged by the finger of the player or it may be operated through the medium of a separate finger-piece associated therewith.

Referring to the accompanying drawings, 40

Figure 1 represents in plan view a portion of a zither provided with one embodiment of my invention.

Figure 2 represents a longitudinal section 45 on the line 2—2 of Figure 1, this view being on a larger scale.

Figure 3 represents a section on the line 3—3 of Figure 2.

Figure 4 is a perspective view showing 50 the support and portions of two hammers attached thereto.

Figure 5 is a plan view of a portion of a zither having applied thereto another embodiment of the present invention.

Figure 6 represents a section on the line 55 6—6 of Figure 5.

Figure 7 represents a section on the line 7—7 of Figure 6.

Figure 8 represents a section on the line 8—8 of Figure 7.

Figure 9 illustrates a portion of a zither, 60 provided with a third embodiment of the invention.

Figure 10 represents a section on the line 10—10 of Figure 9.

Figure 11 illustrates two of the hammers, the actuating members therefor and the finger-pieces for operating said members, all in plan view.

Figure 12 illustrates one of the spacers 70 which is employed in the attachment.

Since the invention does not reside in the construction of the zither itself, I have not illustrated a complete instrument, but of course it will be understood that it may be 75 of any suitable form and that it will be provided with the usual melody strings, and, if desired, with the several groups of chord strings which it is customary to employ.

In Figures 1, 5 and 9, I have shown a 80 portion of a zither, the body of which is indicated as a whole at 20 and which is provided with four groups of chord strings 21, and with melody strings 22 strung to provide a diatonic scale of two octaves. Although I have shown two strings for each hammer which are tuned to the same pitch, 85 I will, for the sake of simplicity, describe the playing attachment as though there were but one string for each hammer.

Referring now to Figures 1 to 4 inclusive, it will be observed that associated with each melody string there is a spring hammer which consists of a head 23 of wood or metal, preferably metal, and a resilient 95 shank consisting of a leaf spring 24. These springs are all secured at one end by any suitable means to a support so as to leave the headed ends free to vibrate. The support comprises a bar 25 arranged substantially 100 in parallelism with the sounding board 26 of the zither and crosswise of the strings, and it is located at the end of the instrument, being attached to the body thereof by any suitable means. As shown, the support 105 may be provided with upright supporting members 27 resting upon the sounding board and it may be attached to a metal case

28 secured to the end wall 29 of the body of the zither by fastenings 30. In cross section, the support bar 25 is of the shape shown in Figure 2; that is to say, it is provided along the inner margin with an upwardly swelled or convex portion 31, and the hammers are fastened at points in the rear thereof so that the hammers normally extend longitudinally of the strings but are at an angle thereto so that their heads are relatively remote from said strings. When the hammers are depressed, they are bent around the curved surface of the convex portion of the support, as illustrated in the last-mentioned figure.

Associated with each hammer there is a member which is indicated as a whole at 32. These members I have termed hammer-actuating members but they also serve other purposes as will be described. Each of these members, as illustrated in Figures 1 to 4 inclusive, consists of a bar arranged longitudinally of the hammers and lying directly thereabove. They are all pivoted upon a pivot 33, which may consist of a cylindrical rod or wire, the ends of which are mounted in blocks 34 located upon the rear portion of the cross bar 25. Between the several members 32, there are spacers 35 likewise affixed to the bar 25 and to a top bar 39. Each member at its free end rests upon and is supported by its associated hammer and is shown as provided with a strip of cushioning material 36 for engagement with the free end of the hammer, or, if desired, with the head thereof. Between its ends, each member 32 is formed with a downward or lateral projection 37 for engagement with the spring intermediate of the head and fixed end of the latter, when the member is depressed. It will thus be seen that, when the member is moved towards the string, the free end thereof will impel the head of the hammer towards the associated string and that thereafter the projection 37 will engage the spring shank of the hammer and force it towards the string. To limit the movement of the member towards the string, it is arranged to engage the support 25. To this end, it is provided with a block or strip 38 of cushioning material so as to deaden the impact upon the support. It makes no difference whether the member is stopped in its movement toward the string by its engagement with the support 25 or with that portion of the spring shank which rests at that time upon the support. In the present instance, the cushion 38 on the member engages the shank of the spring near its fixed portion at a point where it is bent over the convex surface of the swelled portion 31 of said support. In any event, the movement of the member 32 toward the string is limited and the member comes to a state of rest at a point where it

is approximately parallel with the string, as shown in Figure 2. The projection 37 on the member defines the node of vibration of the free end of the hammer and performs the function of a stationary rest against which the spring shank is pressed by the resiliency of that portion which lies between the projection 37 and the fixed end of the said shank. As soon as the hammer-actuating member is released, the resiliency of the spring hammer returns said member to its normal inactive position, and, as the said member swings upwardly about its pivot, the head of the hammer engages the free end thereof and is held against vibration. Each hammer actuating member, as thus described, performs several functions. It actuates the hammer, impelling the free weighted end thereof toward the string so as to cause it to impinge thereon with considerable force; it provides a rest or temporarily fixed member about which the headed end of the hammer vibrates; and it also serves as a stop to damp the vibrations of the hammer when the latter has been released and permitted to return to normal inactive position. Thus the single member performs the functions which hitherto required at least two if not three separate members or parts.

It is not essential that the invention broadly should take the form which has thus been described. In Figures 5 to 8 inclusive, I have illustrated another embodiment of the invention in which the several parts are constructed somewhat differently from those which I have described. In these figures, the spring hammers are not affixed to a stationary support, but their relatively fixed ends are attached to the hammer-actuating members. In these figures, each of the hammer-actuating members is indicated as a whole at 40. It consists of a bar movable about a fixed pivot 41, and it is provided at its pivoted end with a downwardly extending arm 42. The pivot or rod 41 is secured to blocks 43 arranged within a metal case 44 attached to the end of the instrument. Within the case, there is the cross bar 45, a top bar 46 and a lower or stop bar 47, as shown in Figure 8.

The end block 43 and the bars 45, 46, 47 all constitute a support. To maintain the hammer-actuating members in their spaced relation, spacers 48 are placed between them. The arms 42 of the hammer-actuating members are limited in their movement in opposite directions about the pivot 41 by the bar 45 and the bar 47, so that said hammer-actuating members can occupy only the extremes of movement indicated in Figure 6. The shanks of the hammers in this case rest upon a transverse rod 50, the ends of which are fixed in ears 51 formed on the ends of the case 44, and the rear ends of the shanks 130

are forced into slots formed in the arms 42 of the hammer-actuating members. As a result of this construction, the resiliency of the spring hammers between their points of engagement with the cross rod 50 and with the arms of the hammer-actuating members is such as to cause said hammers to assume a normal inactive position with the free ends of said members relatively remote from the 10 associated strings and with the arms 42 in engagement with the stop bar 47. The free ends of the hammers also, when said members are in the position last described, engage cushions 52 on the under side of the 15 ends of said members and assist in holding said members in their inactive position. Between their ends the hammer are provided with downwardly extending projections 53, which, when the hammers and 20 members are in inactive position, do not engage the spring shanks of the hammers, but which, when the members are depressed, eventually engage the spring hammers at points relatively near the cross rod 50 and 25 force the hammer into engagement with the strings. After a hammer head strikes the string, the headed end of the hammer thereafter vibrates about said projection 53. There are lugs or flanges 54 on the projections which straddle the hammers and assist 30 in preventing lateral dislocation thereof. The hammer-actuating member in the present case performs the functions performed by the equivalent hammers in the construction first herein described.

Referring now to the construction illustrated in Figures 9 to 12 inclusive, spring hammers and hammer actuating members are employed not unlike those last described, 40 but, in addition thereto, I employ keys for actuating said members. In this construction, the support comprises a bar 60 and an end block 61, which may be formed of wood or metal as may be desired, and which may 45 be attached to the body of the instrument in any suitable way. The shanks 24 of the spring hammers rest upon the cross rod 62 and their ends are secured in slots in the arms 63 of the hammer-actuating members 50 64. Said members 64 are pivoted upon a pivot 65, and are spaced apart by spacers 66, of which one is shown in Figure 12. Each hammer-actuating member is provided 55 with a cushion 67 at its free end for engagement with the hammer head to prevent the vibration thereof when it is returned to inactive position after having been actuated. Each hammer-actuating member is likewise provided with the rest or projection 68 to 60 perform the functions of those indicated at 37 and 53 in the two actions hereinbefore described. The keys for operating the various hammers are pivotally mounted upon a pivot 69, which, like the pivot 65 and the 65 rod 62, is arranged transversely of the

strings. Each key is angular in side elevation and is pivoted at its forward end. The rod 69 is in a vertical plane in front of and somewhat remote from the vertical plane of the pivot 65, as shown in Figure 70 10. The tension of the spring hammers when they are in inactive position is sufficient to hold the members 64 against the keys and also to hold the keys with their free ends raised. The rear top portion of 75 each member is flat and each key has two flat surfaces on its under side which form an obtuse angle. Each member 64 extends under the pivot 69 and the free end of each key lies above the pivot 65. Consequently, 80 when the free end of a key 70 is depressed, it swings the key-actuating member downwardly about the pivot 65 until the rear portion of the key rests upon the flat top surface of the member. Upon releasing the 85 key, the hammer returns to its initial position in engagement with the flat surface of the forward end of the key. Thus the hammer and the pivot 65 limit the downward movement of the key, and the key and the 90 pivot 69 limit the upward movement of the member 64. To deaden any sound that may be caused by the operation of the parts, each key is provided at its forward portion with a cushion 71 and each hammer is provided 95 at its rear portion with the cushion 72. When one of the keys 70 is depressed or moved downwardly about the pivot 69, the free end of the hammer-actuating member is moved towards the body of the instrument. 100

The free end of said member impels the hammer head toward the string and the spring shank of the hammer is bent about the rod 62. The projection 68 of the hammer-actuating member serves as 105 a rest about which the free end of the hammer head vibrates. Increased tension is placed upon that part of the spring which lies between the pivot 62 and the arm 63 of the hammer-actuating member. The key 110 may be released after the hammer head has struck the string one blow or it may be held depressed to cause the hammer head to vibrate rapidly against the string and produce a trill or tremolo. As soon as the key is 115 released, the hammer returns the hammer actuating member and the key to their normal inactive positions, and the engagement of the hammer head with the cushion 67 on the member 64 effectively prevents the hammer 120 from vibrating on its return to inactive position.

In all of the actions which I have herein described, the hammer-actuating member performs the function indicated by the term 125 which I have used in connection therewith, and in addition it serves as a stop to prevent the vibration of the hammer when the latter has been released and returned to inactive position; the hammer-actuating member im- 130

pels the head of the hammer toward the string upon the initial movement of the hammer-actuating member; and, by reason of the rest or projection which engages the spring shank, said member causes the completion of the movement of the hammer head toward the string and defines the node of vibration of the headed end of the spring hammer.

10 Having thus explained the nature of my said invention and described a way of making and using the same, although without attempting to set forth all of the forms in which it may be made or all of the modes of its use, what I claim is:

1. A playing attachment for zithers, comprising a plurality of spring hammers, a plurality of actuating members associated with said hammers, and a pivot for said members, said members extending in the same direction as said hammers and having their free ends engaging the free ends of said hammers when the latter are in their normal inactive positions to hold said hammers from vibration, and a projection on each member for engaging the spring shank of the associated hammer and about which the free end of the hammer may vibrate.

2. A playing attachment for zithers, comprising a spring hammer, an actuating member associated therewith and having a free end normally engaging the headed end of the hammer, and a projection on said member for engaging the spring shank of said hammer and about which the free end of the hammer may vibrate.

3. A playing attachment for zithers, comprising a spring hammer, an actuating member associated therewith extending in approximately the same direction and having a free end normally engaging the head of said hammer, a pivot for said member, said hammer being attached to said member adjacent the pivotal point thereof, and a stationary support for said hammer independent of said member.

4. A playing attachment for zithers, comprising a spring hammer, a pivoted actuating member extending lengthwise of the hammer and having a free end normally engaging the headed end thereof, a pivot for said member, and a projection on said member intermediate its ends for engaging said spring hammer intermediate the ends thereof and about which the free end of said hammer may vibrate.

5. A playing attachment for zithers, comprising a spring hammer, a pivoted actuating member extending lengthwise of the hammer and having a free end normally engaging the headed end thereof, a pivot for said member, a projection on said member for engaging said spring hammer intermediate the ends thereof and about which the free end of the hammer may vibrate, and means

for limiting the actuating movement of said member.

6. A playing attachment for zithers, comprising a spring hammer, a pivoted actuating member associated therewith and having a free end normally engaging the headed end thereof, a projection on said member for engaging the hammer between the ends thereof and about which the free end of the hammer may vibrate, a pivot for said member, and means for limiting the movement of said member in opposite directions about said pivot.

7. A playing attachment for zithers, comprising a spring hammer mounted at one end with the headed end free to vibrate, and a pivoted actuating member therefor having a free end normally engaging the headed end and having its free end arranged to impel said headed end toward the associated string on the initial movement of said member, said member having a projection for engaging said spring hammer intermediate the ends thereof and completing the movement of the headed end of said hammer against said string on further movement of said member.

8. A playing attachment for zithers, comprising an actuating member and a headed spring hammer associated with one of the strings, a pivot for the rear end of the actuating member, the rear end of the hammer being attached to the pivoted end of the said actuating member and its headed end normally engaging the free end of the said member, and a fixed member engaged by an intermediate portion of the spring hammer and about which the spring hammer may be bent by the actuating member.

9. A playing attachment for zithers, comprising an actuating member and a headed spring hammer associated with one of the strings, a pivot for the rear end of the actuating member, the rear end of the hammer being attached to the pivoted end of the said actuating member and its headed end normally engaging the free end of the said member, and a transverse member engaged by an intermediate portion of the spring hammer, said actuating member having a projection for engaging the hammer at a point between the transverse member and the hammer head.

10. A playing attachment for zithers, comprising a headed spring hammer, an actuating member pivoted at its rear end and normally having its free end extending in the direction of and engaging the headed end of the hammer, a projection on the said member for engaging the shank of the hammer intermediate the ends thereof, and a key for operating the actuating member.

11. A playing attachment for zithers, comprising a cross rod, a headed spring hammer resting at a point between its ends

- on the cross rod, a pivot parallel with and in the rear of the cross rod, and an actuating member pivoted at one end of the pivot and connected at its pivoted end to the rear end of the hammer, said member having a projection for engaging the hammer in front of said cross rod to operate the hammer.
12. A playing attachment for zithers, comprising a cross rod, a headed spring hammer resting at a point between its ends on the cross rod, a pivot parallel with and in the rear of the cross rod, an actuating member pivoted at one end on the pivot and connected at its pivoted end to the rear end of the hammer, said member having a projection for engaging the hammer in front of said cross rod to operate the hammer, a rearwardly extending finger-piece for operating said actuating member, and a pivot 20 for the front end of said finger-piece.
13. A playing attachment for zithers, comprising a plurality of spring hammers, a plurality of pivoted actuating members, a pivot rod therefor, a plurality of cushions 25 projecting from said members and normally holding the free ends of said hammers from vibrating, means for limiting the movement of said members about said pivot rod, and projections on said actuating members intermediate of the ends thereof about which the headed ends of the hammer may vibrate.
14. In testimony whereof I have affixed my signature.

GEORGE H. NOBBS.
